OTTO GREINER, OF NEW YORK, N. Y., ASSIGNOR TO OTIS ELEVATOR COMPANY, OF JERSEY CITY, NEW JERSEY, A CORPORATION OF NEW JERSEY.

SAFETY DEVICE.

1,268,114.

Specification of Letters Patent.

Patented June 4, 1918.

Application filed June 6, 1914. Serial No. 843,341.

To all whom it may concern:

Be it known that I, OTTO GREINER, a subject of the Emperor of Germany, residing in New York, in the county of New York and 5 State of New York, have invented a new and useful Improvement in Safety Devices, of which the following is a specification.

My invention relates in general to safety devices, and is particularly directed to a 10 safety device for elevators or other vertically reciprocating hoists, although the same may be applied to any load carrying device movable in a vertical, inclined or horizontal path.

15 One object of the invention is the provision of a safety device which will effect a retarding action on the load carrying device substantially the instant the latter attains a predetermined excessive speed.

20 Another object of the invention is the provision of a safety device which will act with gradually increasing brake action during the first stage of operation so as to effect a gentle and positive stop of the elevator car 25 or other load carrying device and thereby obviate all shocks and jars to the hoisting machinery and the live load.

Other objects of the invention will appear hereinafter, the novel combinations of elements being pointed out in the annexed 30 claims.

In the drawings accompanying this specification, Figure 1 is a diagrammatic representation of a typical elevator containing 35 an embodiment of my invention; Fig. 2 is an elevation view of the safety device; Fig. 3 is an end view of Fig. 2; Fig. 4 is a sectional plan view of Fig. 2; Fig. 5 is a modified form of elevator safety operating device.

40 Like reference characters denote similar parts in all of the figures.

Among the many types of safety devices for elevators, there is one which employs a roller which, in the event of excessive car speed or other conditions which call for an emergency stop of the car, is caused to move up an incline and wedge itself between the guide rail and a part on the car. While a safety device of this nature is most reliable 45 in its action and operates with absolute certainty and great power, it is open to the objection that its retarding or braking action

on the car is under certain conditions too severe. This objection is not present to an appreciable degree in case of a slow moving 55 elevator, but where the speed is high as in nearly all of the present day elevators the severity of action of the roll type safety device is such as to preclude its use. In a safety device constructed according to my 60 invention, all of the good features inherent in the wedge roller type of safety device are retained while the one objectionable feature, namely its severity of action, is entirely overcome, so that the elevator car, regardless of 65 its speed or load, may be retarded and brought to rest promptly and gently with absolute certainty and without any danger of a too sudden stop.

Referring to the drawings, the safety device 70 comprises a "safety plank" consisting of the channel beams 2-2, which are preferably carried upon the bottom of the car 3 as shown in Fig. 1. The retarding mechanism is carried upon each end of the safety 75 plank and is adapted to co-act with the parallel steel guide rails 4, 4. Since the retarding mechanism is comprised of two parts which are similar to each other in every respect, a detail description of one of these 80 parts will answer for both.

Each of these parts comprises a pair of heavily constructed jaws 5, 5, which are both pivoted upon a stud 6 carried by a pair of plates 7, 7, secured to the upper and lower 85 sides, respectively, of the channel beams 2, 2. Between the inner ends of the jaws, 5, 5, and located in a recess provided for that purpose is a spring 8, which may be normally inert or else under a predetermined amount 90 of compression, the amount of compression being determined in accordance with the average nominal load on the car. A self-aligning bolt 9 passes through the inner ends of the jaws and prevents the spreading apart 95 of these parts under the influence of the spring 8. The extreme inner end of each jaw is provided with a through bolt 10 which carries a compression spring 11. The head of each bolt 10 bears against the beam 2 under the action of the spring 11 and the purpose of the same is to maintain the jaws as 100 a unit in central position so as normally to prevent the rail-engaging faces of the jaws

from contacting with the sides of the guide rails during the normal travel of the car, and thereby prevent the jaws from wear. The rail engaging end of one of the jaws of a pair of jaws is provided with a recess in which lies a self alining tapered member or wedge 12 (see Figs. 3 and 4) which is adapted to swivel in the said recess in the jaws. A roller 14 preferably made of hardened steel is pivoted in a cage 13 carried upon one end of a rod 16. This roller is normally maintained in contact with the wedge 12 and at a short distance from the side face of the guide rail 4 by means of a small projection or dowel pin 15, which rests in a corresponding hole in the jaw during the normal operation of the car. A plate 17 may be secured to one of each set of jaws and is for the purpose of keeping out all dirt and foreign matter.

The operation of the safety device may be effected in any one of several different ways, such for example as the method shown in Fig. 1, in which the speed of the elevator car is the controlling factor. Referring to this figure it will be seen that I have shown the usual fly ball governor 18 which is driven through the governor cable 19 and is adapted to operate the clamps 20 which grasp the governor cable with a yielding friction when the speed of the car becomes excessive and thereby effects a relative movement between the car and governor cable. The latter is connected to a cable hitch 25 which is connected directly to the rod 16 on the right hand side of the car and indirectly to the rod 16 on the left hand side of the car through a bell crank 21, rod 22 and bell crank 24. A compression spring 23 is associated with the rod 22 and maintains the said rod against movement except at such times as the governor arrests the cable 19. In case of excessive car speed, the governor causes the clamps 18 to grasp and retard the cable 19 and the continued movement of the car causes both of the rods 16, 16, simultaneously to move upwardly carrying with them their respective rollers 14, 14, of the safety device. The initial movement of the rollers carries the projections 15 out of their recesses in the jaws and each roller moves up the sloping face of the corresponding wedge 12 into contact with the side of the guide rail. As soon as a roller engages the rail, the frictional contact therewith assisted by the upward pull being exerted by the governor cable carries the roller upwardly as far as it can go or until the roller cage 13 engages the top of the recess in the jaw.

In the modified form of safety operating device shown in Fig. 5 I use instead of the single spring 23 of Fig. 1 a pair of springs 23' and 23' associated, respectively with each of the rods 16, 16, and bearing against brackets 26, 26, secured to the car. This arrange-

ment while effecting a simultaneous raising of the rod 16, 16, permits of an independent movement of the rods in an upward direction so that in case one rod for some extraordinary reason should refuse to move upwardly the other rod may operate. Regardless of the type of operating device, the resultant braking action is obvious, and may be described as follows: As soon as the roller engages the rail and starts to move up the inclined face of the wedge, the left hand jaw of Fig. 3 tends to move away from the rail and this movement is transmitted through the heavy coil spring 8 to the right hand jaw 5 which is forced into frictional engagement with the rail and exerts a braking action on the car in accordance with the pressure. As the car continues to descend the roller is carried up farther on the sloping face of the wedge and the spring 8 is being compressed, resulting in a corresponding increase in the braking action. This pressure continues to increase until finally the roller reaches its limit of movement and the brake acts with normal power and the car comes to rest gently and gradually and without appreciable loss of time. The slope of the wedge face may be curved or straight as shown and in either case the pitch of the slope is such that the roller will always reach its limit of movement and it is such that the safety is self-locking in its upper position. The braking effect on the car depends almost entirely upon the spring 8 and on the nature of roller and surface of a jaw against the rail, also nature of surface of the rail. While the braking power due to the action of the spring will depend upon the strength of the spring in its initial compression when the roller is in end position, by properly proportioning the wedge and by choosing a spring of the proper strength and deflection the retarding action of the safety device may be varied within wide limits so as to suit all conditions of load and speed. Since the wedge member 12 is self alining due to the manner in which it is carried in the jaw, the roller when brought into action will always engage the rail face fairly and bear evenly upon the rail over the entire length of the roller. In this manner the rail will never become scored or damaged even after many operations of the safety device, as many experiments with this type of safety device have proved. Since the jaws are held in operated position by spring pressure, the same will automatically adjust themselves to inequalities or bends in the guide rails.

The function and operation of the spring 8 is substantially different than that of other safety devices which employ a spring to move the jaws against the guide rails. In this latter type of safety device, the spring is constantly under its maximum pressure

and may remain in that condition for weeks or months at a time or until the safety device is called into operation. It has been found that under these circumstances the spring 5 is very apt to acquire a permanent set. Furthermore, in extreme cases the spring may become broken or otherwise unable to perform its proper functions when the time comes, and, owing to its position under the 10 car, where its condition is not readily seen, there is no ready way of ascertaining whether it is in proper operative condition or not. Then again, when a safety device of the usual spring applied type, comes into 15 action, the braking effect is called into play instantly with maximum power resulting in a very abrupt stop of the car, which is most undesirable.

In a safety device containing an embodiment of my invention, the spring 8 under normal running conditions is either free from all compression entirely or at most is compressed but slightly, or to a limited degree, so that there is no possibility of the 20 spring becoming deformed or acquiring a permanent set, and it is therefore always in proper operating condition. The operation of my invention effects a cumulative retarding action on the car. That is to say in the 25 first stage of action, the initial braking power is at a minimum and gradually increases to a maximum, the result being to effect a smooth and gradual stop of the car without shocks or jars. The power of the 30 safety device is not dependent upon the variable and uncertain retardation of the governor cable due to the grasp of the governor clamps upon the cable, but is dependent upon the action of the springs 8 which 35 in every case will act uniformly, the governor cable serving merely to effect the operation of the wedge rollers.

In nearly every instance the safety device may be reset by merely applying power to 40 raise the car, whereupon all of the parts of the device will automatically assume their respective positions ready for a subsequent action. Where the hoisting power is not sufficient to effect this result it is a simple 45 matter for the elevator attendant to push the rollers back into position by means of a rod or crank or other suitable means operated from the inside or outside of the car or to release the spring.

50 While I have described one embodiment of my invention in connection with an elevator car also a well known and extensively used method for effecting its operation, it is obvious that the same may be changed 55 structurally in various details without departing from the spirit or scope of the invention. Furthermore the method of operating the safety device here shown is merely 60 by way of example and is but one of many 65 ways in which the device may be operated.

While the safety device is particularly adapted to passenger or freight elevators which travel in a vertical path, the same may be used with equal advantage in connection with inclined or horizontally moving 70 load carrying devices as well as in many other connections in which it is desired to apply an emergency brake to a moving member.

What I claim is:—

75 1. An elevator safety device comprising clamp jaws adapted to co-act with a stationary member, means for effecting an engagement between said jaws and member tending to separate the jaws, and an elastic medium 80 opposing said separation of the jaws.

2. In an elevator safety device, the combination of a car and guide rails, of pivoted clamp jaws on the car adapted to co-act with a guide rail, means for effecting an engagement 85 between said jaws and rail tending to move apart the jaws, and a spring opposing the movement of said jaws.

3. In an elevator safety device, the combination of a car and guide rails, of pivoted 90 clamp jaws on the car adapted to co-act with a guide rail, a member adapted to be wedged between said rail and one of the jaws tending to move the jaws apart and a spring opposing said movement.

95 4. In an elevator safety device, the combination of a car and its guide rails, of pivoted jaws on the car adapted to clamp a guide rail, a roller adapted to be wedged between one of the jaws and a guide rail tending to 100 separate the jaws, and a spring opposing the separation of the jaws.

5. In an elevator safety device, the combination of a car and its guide rails of jaws on the car adapted to clamp a guide rail, a 105 roller adapted to be wedged between one of the jaws and a guide rail tending to separate the jaws, and a spring opposing the separation of the jaws.

6. In an elevator safety device, the combination of a car and its guide rails, of pivoted jaws on the car adapted to clamp a guide rail, a roller adapted to be wedged between one of the jaws and a guide rail tending to 110 separate the jaws, and means 115 opposing the separation of the jaws.

7. In an elevator safety device, the combination of a car and its guide rails, of pivoted jaws on the car adapted to clamp a guide rail, and a self-aligning roller adapted 120 to be wedged between one of the jaws and a guide rail tending to separate the jaws.

8. In an elevator safety device, the combination of a car and its guide rails, of pivoted jaws on the car adapted to clamp a guide 125 rail, a self aligning roller adapted to be wedged between one of the jaws and a guide rail tending to separate the jaws, and a spring opposing the separation of the jaws.

9. In an elevator safety device, the com- 130

- 5 bination of a car and its guide rails, of pivoted jaws on the car adapted to clamp a guide rail, a member adapted to be wedged between one of the jaws and a guide rail so as to move said jaw away from the rail, and means for communicating the movement of one jaw to the other jaw.

10 10. In an elevator safety device, the combination of a car and its guide rails, of pivoted jaws on the car adapted to clamp a guide rail, a member adapted to be wedged between one of the jaws and a guide rail so as to move said jaw away from the rail, and yielding means for communicating the 15 movement of one jaw to the other jaw.

15 11. In an elevator safety device, the combination of a car and its guide rails, of pivoted jaws on the car adapted to clamp a guide rail, a self-aligning member adapted to be wedged between one of the jaws and a guide rail so as to move said jaw away from the rail, and yielding means for communicating the 20 movement of one jaw to the other jaw.

20 12. In an elevator safety device, the combination with an elevator car and its guide rails, of pivoted jaws carried on the car adapted frictionally to engage a guide rail, a roller adapted to be wedged between a jaw and the guide rail tending to move said jaw away from the rail, and resilient means for transmitting the movement of one jaw to the 25 other jaw.

25 13. In an elevator safety device, the combination with an elevator car and its guide rails, of pivoted jaws carried on the car adapted frictionally to engage a guide rail, a roller adapted to be wedged between a jaw and the guide rail tending to move said jaw away from the rail, and a spring for transmitting motion between the jaws.

30 14. In an elevator safety device, the combination with a car and its guide rails, of a pair of pivoted jaws carried on the car adapted frictionally to engage a guide rail, a wedge carried by one jaw, a roller between the wedge and rail, an elastic medium associated with both jaws, and means for controlling the roller.

35 15. In an elevator safety device, the combination with a car and its guide rails, of a pair of pivoted jaws carried on the car adapted frictionally to engage a guide rail, a wedge carried by one jaw, a roller between the wedge and rail, means for moving said roller upon said wedge into engagement with the rail and thereby rock one of the jaws on its pivot, and a spring for transmitting the movement of one jaw to the other jaw.

40 16. In an elevator safety device, the combination with a car and its guide rails, of a pair of pivoted jaws carried on the car and adapted frictionally to engage a guide rail, a spring associated with said jaws and arranged to transmit pressure equally between 45 the jaws, and means for effecting a compression of said spring during the operation of the jaws.

45 17. In an elevator safety device, the combination with a car and its guide rails, of a pair of pivoted jaws carried on the car and adapted frictionally to engage a guide rail, a spring associated with said jaws and arranged to transmit pressure equally between the jaws, and means comprising a wedge for effecting a compression of said spring during the movement of one of the jaws.

50 18. In an elevator safety device, the combination with a car and its guide rails, of a pair of pivoted jaws carried on the car and adapted frictionally to engage a guide rail, a spring associated with said jaws, and means comprising a wedging roller intermediate a jaw and guide rail for effecting a compression of said spring during the operation of one of the jaws.

55 19. In an elevator safety device, the combination with a car and its guide rails, of a pair of clamp jaws pivoted to the car and normally out of contact with a guide rail, said jaws being movable as a unit about said pivot, and means comprising a spring for maintaining the jaws in normal position with respect to a guide rail.

60 20. In an elevator safety device, the combination with a car and its guide rails, of a pair of clamp jaws pivoted to the car and normally out of contact with a guide rail, said jaws being movable as a unit about said pivot, and resilient means for maintaining the jaws in normal position with respect to a guide rail.

65 21. In an elevator safety device, the combination with a car and its guide rails, of a pair of clamp jaws pivoted to the car and normally out of contact with a guide rail, said jaws being movable as a unit about said pivot, and means comprising a spring associated with a jaw for maintaining the jaws in normal position.

70 22. In an elevator safety device, the combination with a car, of a pair of levers pivoted intermediate their ends to the car, a guide rail for the car positioned between the ends of the levers on one side of the pivot, a spring positioned between the ends of the levers on the opposite side of the pivot, and a member adapted to be wedged between the said rail and one of the levers to effect a compression of the spring and thereby move the other lever into frictional engagement with the said guide rail.

75 23. In an elevator safety device, the combination with a car, of a pair of levers pivoted intermediate their ends to the car, a guide rail for the car positioned between the ends of the levers on one side of the pivot, a normally inert compression spring positioned between the ends of the levers on the opposite side of the pivot, and a member

adapted to be wedged between the said rail and one of the levers to effect a compression of the spring and thereby move the other lever into frictional engagement with the said guide rail.

24. An elevator car, guide rails therefor, pivoted safety clamps on the car co-acting with a guide rail, a wedge roller for effecting the operation of the clamps, and a spring adapted to be compressed during the operation of the clamps and controlling the power of the clamps.

25. In an elevator safety device, the combination of a car and guide rails, of pivoted clamping members carried on the car adapted to co-act with a guide rail, means for effecting an engagement between said clamping members and guide rail tending to move apart the clamping members, and a spring opposing the movement of the said members.

26. In an elevator safety device, the combination of a car and guide rails, of pivoted clamping members carried on the car adapted to co-act with a guide rail, a member adapted to be wedged between said guide

rail and one of the clamping members tending to move the clamping members apart, and a spring opposing said movement.

27. In an elevator safety device, the combination of a car and its guide rails, of pivoted jaws on the car movable as a unit about their pivot adapted to clamp a guide rail, and means comprising a spring for equalizing the pressure of the jaws on the rail when moved into clamping position.

28. In an elevator safety device, the combination of a car and its guide rails, pivoted clamp jaws on the car adapted to engage said rails, said jaws being movable as a unit about their pivot, and resilient means for equalizing the pressure of said jaws on a guide rail when the jaws engage the said rail.

In testimony whereof, I have signed my name to this specification in the presence of two subscribing witnesses.

OTTO GREINER.
